Application January 23, 1956, Serial No. 560,732

Claims priority, application Germany January 25, 1955

2 Claims. (Cl. 214—503)

The present invention relates to a trash collection truck with a feeder or scoop for transferring the trash from the charging container into a collector.

With heretofore known trash collection trucks of the above mentioned type, certain difficulties have been encountered with regard to the transfer of the trash from the charging container to the collector. A particular difficulty is due to the fact that the trash is composed of highly varying substances and that the customary feeding means not infrequently encounter great resistance in their transferring operations which cause a canting of the transferring buckets or scoops. Particularly piston or scraper-like acting transferring devices which are to be moved parallel to each other are subject to the said difficulties, especially if they not merely transfer the trash from the charging container to the collector but also have to compact the trash in the collector.

For purposes of simplification and improving the reliability of the transfer from the charging container to the collector, it has been suggested instead of employing transfer means to be moved parallel to each other, to employ tiltable buckets or the like and to tilt the same about a horizontal axis. However, the small stroke in the neighborhood of the tilting axis brings about that a simple transfer bucket cannot satisfactorily perform the double task of transferring and compacting. Therefore, the piston-like operating transfer member has additionally been provided with a tiltable transfer member which is intended to compact the trash prior to its transfer from the charging container to the collector. The above mentioned drawback inherent to a parallel displacement of the transfer or conveying members is, however, not obviated by such an arrangement.

It has furthermore been suggested in addition to a rear wall of the collector, which wall is tiltable about an upper vertical axis, to provide a second damming up wall which is tiltable about an adjacent axis and which is intended to prevent the trash moved into the collector from falling back into the charging container. This arrangement has the drawback that trash enters between the transfer member and the damming up wall and thus impedes the movement of the tiltable elements.

In a further effort to overcome the above mentioned drawbacks, it has also been suggested in addition to providing a charging bucket tiltable about a lower horizontal axis to employ a second bucket journaled at an intermediate height, against the outside of which the trash is first compressed whereupon after tilting of said second bucket the trash is transferred by the first bucket into the collector. This type of pre-compacting prior to the transfer from the charging container to the collector is likewise unsuitable for a compacting of the entire contents.

It is, therefore, an object of the present invention to provide a trash collector truck with means which will overcome the above mentioned drawbacks.

It is another object of this invention to provide a trash collecting truck with a simplified arrangement for re-

2

ceiving the trash from the trash cans being emptied and for transferring the thus unloaded trash into the collecting compartment of the truck while preventing trash in the collecting container during the transferring operation and during the movement of the truck from dropping back into the charging container into which the trash cans are emptied.

It is still another object of this invention to provide a trash collecting truck of the above mentioned type which while providing a reliable and simplified arrangement for conveying the trash from a charging container into a collector will be free from transferring members moving parallel to itself.

These and other objects and advantages of the invention will appear more clearly from the following specification in connection with the accompanying drawings, in which:

Fig. 1 represents a side view of a trash collecting truck according to the invention, the charging container into which the trash is unloaded and the collector occupying their position for receiving trash.

Fig. 2 is a side view similar to that of Fig. 1 but showing the charging container and the collector in lifted position for discharging the collected trash.

Fig. 3 shows on a somewhat larger scale than that of Figs. 1 and 2 a longitudinal section through the charging container and cooperating bucket and scoop members, said section being taken along the line III—III of Fig. 8.

Fig. 4 is a section similar to that of Fig. 3 but taken along the line IV—IV of Fig. 8 and showing the bucket and scoop members in a position different from that occupied by the same in Fig. 3.

Figs. 5, 6 and 7 represent sections similar to those of Figs. 3 and 4 but showing different phases of operation.

Fig. 8 is a section along the line VIII—VIII of Fig. 7.

Fig. 9 is a diagrammatic representation of the control mechanism for hydraulically operated cylinder piston systems arranged to actuate the charging bucket and transferring scoop for the trash receiving and transferring means.

Fig. 10 is a partial section taken along the line X—X of Fig. 9.

General arrangement

The trash transfer arrangement for transferring the trash from the charging or receiving container to the collector is characterized primarily by two tiltable buckets or scoops each of which is tiltable about a horizontal axis. The lower one of the said two buckets or scoops forms part of the receiving container and simultaneously serves as the bottom thereof. More specifically, the invention consists primarily in that the second bucket or scoop is tiltable about an axis at the upper end of the connecting opening between the receiving container and the collector, and following the lifting movement of the first bucket or scoop compresses the trash into the collector. The trash transfer arrangement according to the invention is furthermore characterized in that the second scoop or bucket holds back the trash transferred into the collector until additional trash is to be transferred into the collector.

It is only at that moment that the upper bucket or scoop is tilted back and the lower bucket or scoop is lifted. Thus, it is impossible with the arrangement according to the present invention that trash which has been transferred into the collector will drop back into the receiving container. Inasmuch as the transfer elements, i. e. the two buckets or scoops do not move parallel to themselves but perform proper and pure tilting movements, the movement of said elements along a predetermined and specifically defined path is always assured.

According to a further development of the invention, the lower bucket or scoop is designed as receiving bucket,

and the rear wall of said receiving bucket is so designed or shaped that the upper bucket will during the upward tilting movement of the lower bucket slide between the trash and the rear wall of the receiving bucket. At these points the upper scoop or bucket encounters minor resistance only even if the trash comprises hard subjects. The design of the lower scoop or bucket as receiving bucket has the advantage that sealing gaps are avoided through which fine ash may trickle. Within the aspect of the present invention, the receiving bucket is intended first to receive the trash from the trash cans being emptied. To this end, it is desirable that the receiving bucket will during the emptying of the can occupy a rather low position so that the trash cans will not have to be lifted too high. The further task of the receiving bucket consists in that it must lift the received trash to a level from where the trash can properly be conveyed into the trash collecting chamber henceforth called trash collector, by means of a second bucket or scoop. It has proved advantageous to arrange the tilting axis of the receiving bucket somewhat above the bottom of the trash collector so that the trash will find a proper rest at the rear end of the trash collector and will not drop back into the receiving container when the upper bucket or scoop is tilted back.

A particularly compact design of the receiving container and the feeding mechanism is obtained when the axes of the two buckets or scoops are completely or nearly vertically located above each other. The upper axis is expediently arranged approximately at the level of the upper edge of the trash collector.

Structural arrangement

Referring now to the drawings in detail, the trash collection truck comprises in customary manner a cab 1 and a collector 2 which is open at the rear side only. The rear end of the collector supports the charging or receiving container 3 into which the trash cans are emptied. The receiving container 3 is tiltably journaled about an upper axis defined by the studs 4. Within the receiving container there is arranged a receiving or charging bucket 5 which is tiltably about a lower horizontal axis defined by the studs 6. Substantially vertically above said last mentioned axis, and in the neighborhood of the axis defined by the studs 4 there are journaled studs 7 connected to the scoop 8 which is tiltably about an axis defined by said studs 7.

Fig. 2 shows the collector 2 tilted about the axis 10 at the rear of the chassis 9. The tilting of the collector 2 is effected by a hydraulically operable cylinder piston assembly 11. It will be obvious that when the collector is tilted from Fig. 1 into Fig. 2 position, the trash slides toward the rear. A tackle or cable line 12 has its front end connected to the chassis 9 and while passing over pulleys 13, 14 around the collector has its rear end connected to a point 15 of the receiving container 3 so that the latter is tilted into open position when the collector tilts about the axis defined by the studs 4 so that the trash is allowed to slide out of the collector.

The receiving container is illustrated on a somewhat larger scale in Fig. 3 and shows the charging bucket 5 in its lowermost position in which it is filled with trash. As will be clearly evident from the drawing, the bucket 5 consists of two arched walls 20, 21 which together with each other and the two side walls 22 (Fig. 8) form a trough located between the side walls 3' of the receiving container 3. The lateral walls of the charging bucket 5 are sealed with regard to the lateral walls 3' by means of felt strips 23. The upper edge of the wall 21 is provided with a ledge 24, for instance of rubber or wood so that the trash can be set down thereon when the trash can is to be emptied. The cylinder 25 forming part of the cylinder piston assembly by means of which the bucket 5 is to be tilted is provided with studs 26 which are journaled in a fork 27 connected to the bucket 5. The piston rod 28 is linked to the stud 30 arranged in a

pocket 29 of the receiving container 3. The pocket 29 forms an enlargement of a hollow beam 31.

Fig. 3 shows the scoop 8 in its left-hand end position in which it closes the rear portion of the collector 2 so that trash cannot drop out of the collector. The scoop 8 is actuated by a cylinder piston assembly comprising the cylinder 35. The cylinder 35 is journaled about the studs 36 in a fork 37 connected to the receiving container. The piston rod 38 is linked at 39 to the scoop 8.

Fig. 4 shows the first phase of the trash transfer from the bucket 5 to the collector 2. As will be seen from Fig. 4, the scoop 8 has been tilted into its right-hand end position with regard to the drawing by the working cylinder 35, whereas the bucket 5 filled with trash still occupies its lowermost position.

The next phase of the trash transfer movement is illustrated in Fig. 5 according to which the bucket 5 has been tilted into its uppermost position by means of the working cylinder 25. During this upward movement of the bucket 5, the scoop 8 has slipped into the bucket 5 between the outer wall 21 and the trash in the bucket 5.

The next step of the trash transfer movement consists in tilting the scoop 8 from its Fig. 5 position into the Fig. 6 position. As will be seen from Fig. 6, the scoop 8 has pushed the trash in bucket 5 out of the latter and has pushed said trash into the collector 2 while simultaneously compacting the trash when the collector is rather filled. The bottom wall 20 of the bucket 5 is arched in such a manner as to conform to the path of movement of the tip of scoop 8. The wall 40 of the hollow beam 31 is arched so as likewise to conform to the path of movement of the tip of scoop 8 on its way from the bucket 5 into the collector 2. After the bucket 5 has been emptied in the manner just described, the working cylinder 25 returns the bucket 5 to its starting position as shown in Fig. 7 in which the bucket 5 can again be filled with trash from trash cans emptied thereinto. The scoop 8 remains in Fig. 6 position so as properly to close the opening of the collector and preventing trash from dropping back from the collector into the bucket 5.

The control circuit for the working cylinders 25 and 35 is illustrated in Fig. 9 in which the cylinder 25 for the actuation of the bucket 5 has reciprocably mounted therein a piston 25a. The cylinder 35 has reciprocably mounted therein a piston 35a for actuating the scoop 8. The cylinder 25 at both sides of the piston 25a communicates with conduits 41 and 42 respectively adapted to convey a pressure fluid such as oil under pressure to and away from the piston 25a. Similarly conduits 43 and 44 lead to opposite sides of the piston 35a for conveying a pressure fluid to and withdrawing a pressure fluid from piston 35a as will be described in detail later.

The control arrangement for use in connection with the trash transfer mechanism according to the invention furthermore comprises a casing 50 having journaled therein a control shaft 51. The control shaft 51 is provided with two control cams 52 and 53 which are of the same design but arranged in an inverse manner with regard to each other. The control shaft 51 is actuated by a hand lever 54. Each of the cams 52 and 53 are in alignment with a pair of valve spools 55 and 55a respectively which respectively control the flow of fluid of passages 56 and 57 provided in casing 50.

A gear pump 60 withdraws oil for the working cylinders from a fluid reservoir 61 and feeds the oil through a conduit 62 into the passages 56 and 57 in casing 50. In the specific position shown in Fig. 9, the oil under pressure pumped by the gear pump 60 passes from conduit 62 through passage 56 into conduit 63 and from there through conduit 44 below the piston 35a. Inasmuch as the upper portion of cylinder 35 above the piston 35a communicates with the reservoir 61 through conduits 43, 42, passage 57 and conduit 74, the piston 35a is moved upwardly thereby tilting the scoop 8 from Fig. 3 position into Fig. 4 position. When the piston approaches

its end position as shown in Fig. 4, an abutment 64 connected to the piston rod 38 engages and opens the valve 65 so that pressure fluid will now pass from conduit 63 to valve 66, open the latter and through conduit 41 will act upon the upper side of piston 25a. As a result thereof, the cylinder 25 moves outwardly (upwardly with regard to Fig. 9) thereby tilting the bucket 5 from Fig. 4 into Fig. 5 position.

The lever 54 is now shifted by 180° so that the cams 52 and 53 reverse their positions. As a result thereof, the upper spool 55 is pressed downwardly (with regard to Fig. 9) by spring 70, whereas the lower spool 55 is pressed downwardly by cam 52 against the thrust of spring 71. Similarly the upper spool 55a is pressed upwardly by cam 53 against the thrust of spring 72, while the lower spool 55a is pushed upwardly by spring 73. Consequently the oil under pressure from conduit 62 now passes through conduit 70 and conduit 57 into conduit 42 and from there through conduit 43 into the upper portion of cylinder 35. As a result thereof, the piston 35a is moved downwardly thereby causing the scoop 8 to move from Fig. 5 position into Fig. 6 position. The oil from the lower portion of cylinder 35 escapes through conduit 63, passage 56 and conduit 74 into the reservoir 61. The pressure fluid in conduit 42 also acts upon the lower surface of the piston 25a. However, in the position shown in Fig. 9 the fluid above the piston 25a cannot escape inasmuch as the valve 66 is closed so that piston 25a cannot move. However, when the piston 35a has substantially reached the end of its downward movement, the arm 64 engages and opens the check valve 66, thereby allowing escape of fluid above the piston 25a through conduit 41, check valve 66, check valve 65, conduit 63, passage 56 and conduit 74 into the reservoir 61. Consequently the cylinder 25 now moves downwardly with regard to Fig. 9 (upwardly with regard to Fig. 6), thereby tilting the bucket 5 back into Fig. 7 position. The trash transfer mechanism thus occupies again its starting position in which a new trash load can be filled into the bucket 5.

The control cams 52 and 53 are so designed that the valve spools 55 and 55a will open the passages 56 and 57 throughout when the lever 54 is shifted by 90° only so that the oil from the control casing 50 can directly return to the reservoir 61 through the return conduit 74.

It is, of course, understood that the present invention is, by no means, limited to the particular construction shown in the drawings but also comprises any modifications within the scope of the appended claims. Thus, the control shaft 51 with the cams 52, 53 and the four valve spools 55 and 55a may also be replaced by a single slide valve with correspondingly designed control channels. The control by a cam shaft has been shown for purposes of clarity only. Furthermore it is also possible so to design the control system that by means of a single adjustment of the lever 54 all four movements of the bucket 5 and scoop 8 will be controlled.

What I claim is:

1. In combination in a trash collecting truck: a collecting container having an opening at one end thereof, a receiving container arranged adjacent to and having a discharge opening at said one end, said receiving container including bucket means forming the bottom of said receiving container and being tiltable about a substantially horizontal axis from its normal trash receiving position into an elevated discharge position for the transfer of trash from said receiving container into said collecting container through said discharge opening, scoop means tiltable about a substantially horizontal axis near

the upper end of said discharge opening, said scoop means normally closing said discharge opening, said bucket means having two substantially parallel side walls and also having therebetween a curved front wall and a curved rear wall connected to each other along a line, the curvature of said front wall following a circle having its center of curvature located on the tilting axis of said scoop means when said bucket means occupies its discharge position, and said rear wall having a curvature following a circle having its center of curvature located on the tilting axis of said bucket means, a curved stationary extension means extending substantially from the tilting axis of said bucket means inwardly into said collecting container and being curved along a circle having its center of curvature located on the tilting axis of said scoop means so that when said bucket means occupies its discharge position said extension means forms with said front wall a continuously curved path for the trash to be discharged, and actuating means operable to tilt said scoop means away from its normal position in which it closes said opening into unloading position in which it is partly within said bucket means when the latter is in its elevated position, said actuating means also being operable to tilt said scoop means from its unloading position back to its normal position.

2. In combination in a trash collecting truck: a collecting container having an opening at one end thereof, a receiving container arranged adjacent to and having a discharge opening at said one end, said receiving container including bucket means forming a displaceable bottom of said receiving container and being tiltable about a substantially horizontal axis from its normal trash receiving position into an elevated discharge position for the transfer of trash from said receiving container into said collecting container through said discharge opening, scoop means tiltable about a substantially horizontal axis near the upper end of said discharge opening, said scoop means normally closing said discharge opening, a first cylinder piston assembly operatively connected to said bucket means for tilting the same about its tilting axis, a second cylinder piston assembly operatively connected with said scoop means for tilting the same away from its normal position in which it closes said opening into unloading position in which it is partly within said bucket means when the latter is in its elevated position, said second cylinder piston assembly also being operable to tilt said scoop means from its unloading position back to its normal position for transferring trash from said bucket means in its elevated position into said collecting container, control circuit means including valve means associated with said cylinder piston assemblies for controlling the same, and a master control member operable to control said control circuit means for controlling the flow of fluid to said cylinder piston assemblies so as to cause the same successively to move said scoop means into its unloading position and said bucket means into its elevated discharge position and to move said scoop means into its closing position and to return said bucket means to its normal position.
